UNITED STATES PATENT OFFICE.

ANDREW JOHAN, OF NEW YORK, N. Y.

APPARATUS FOR COALING SHIPS AT SEA.

No. 903,094.

Specification of Letters Patent.

Patented Nov. 3, 1908.

Application filed April 28, 1908. Serial No. 429,716.

To all whom it may concern:

Be it known that I, ANDREW JOHAN, a citizen of the United States, and a resident of the city of New York, borough of Brooklyn, in the county of Kings and State of New York, have invented a new and Improved Apparatus for Coaling Ships at Sea, of which the following is a full, clear, and exact description.

10 This invention is an improved apparatus for transferring at sea, material from one ship to another; relating more especially to the coaling of war vessels from colliers. This is accomplished in accordance with my 15 invention by placing a collier in tow of the vessel and providing one or more traveling cables between them, on which the coal or other material is carried, the said cables having means operatively connected therewith to maintain them under constant and equal tension during the rolling and pitching of the boats in heavy seas, this constant and equal tension on the cables being maintained irrespective of the tension on, or 25 slackness of, the hawser connecting the two boats together.

Reference is to be had to the accompanying drawings forming a part of this specification, in which similar characters of reference indicate corresponding parts in all the views.

Figure 1 is a diagrammatic view in side elevation, illustrating the nature of my improvements; Fig. 2 is a plan of the same; 35 Fig. 3 is a side elevation, on an enlarged scale and partly in section, of that portion of the apparatus which is applied to the collier; Fig. 4 is a plan of the same; Fig. 5 is a side elevation, on an enlarged scale, of that 40 portion of the apparatus applied to the vessel to which the coal or other material is to be transferred; Fig. 6 is a plan of the same; and Fig. 7 is a perspective view of the 45 means by which the coal or other sacks are detachably applied to the transfer cables.

Referring more especially to Figs. 1 to 4, illustrating that portion of the apparatus which is applied to the collier or other vessel from which the material is to be transferred, 50 the same consists of a suitable supporting frame 10, of considerable length, carried on the deck of the boat at the stern, and is provided with longitudinal slots 11, at each side, extending approximately its full length. 55 In these slots is laterally slidable a cross-

beam 12, which is also adapted to laterally swing, and is held against endwise movement by curved shoes 13 attached thereto at the inside of the frame. A cable 14 is attached at each side of the center and to the rear of the cross-beam, and passes one or more times about a roller or sheave 15 journaled at the rear end of the frame, with the free ends of the cables attached to a weight 16 movable within a well 17 provided in the 60 boat.

At each end of the cross-beam 12 is journaled a sheave 18 at the outside of the frame, and at the inside of the frame the cross-beam is provided at the front at each 70 side of its center with a sheave 19.

The apparatus carried by the vessel to which the coal or other material is delivered, as best shown in Figs. 5 and 6, comprises a suitable supporting frame 21 mounted on the 75 deck at the bow and carrying a cross-shaft 22, journaled near its top, to the outer ends of which are fixed sheaves 23, the shaft being driven from a motor or other suitable source of power 24, by a chain 25 passing 80 from a sprocket wheel 25^a fixed to the driving shaft, over a sprocket wheel 25^b attached to the shaft 22. Forward of the frame 21, a somewhat narrower supporting frame 26 is provided, the same also carrying a cross-shaft 27, corresponding to the shaft 22 of the frame 21 and having sheaves 28 attached to its outer ends, the shaft 27, as shown, being driven by a motor 29 through a chain 30.

At the outside and at the opposite sides of 90 the frames 10, 21 and 26, platforms 31, 32 and 33 are respectively provided for supporting the operators, the platforms in the case of the frame 10 extending its full length, and the platforms of the frame 21 having 95 coal chutes 34 leading therefrom below deck to the coal bunkers or other convenient point. At the front of the sheaves 23 and 28, just above the platforms 32 and 33 respectively, are projecting arms 32^a, 33^a, 100 providing stops for a purpose hereinafter made apparent.

In the use of the apparatus, a collier or other vessel having the frame 10 takes the vessel having the receiving portion of the apparatus in tow, the two boats being thus connected together by a hawser 35. Cables 36 and 37 are extended from one vessel to the other before they separate, and are respectively passed over the sheaves 18, 23, 19 and 110

28, the cables being of such length that when the hawser 35 is under a pull, the cross-beam 12 will be well advanced to the stern, and the weight 16 will be at or near the top of the well 5 17. By this construction the cables will be maintained under a constant and equal tension irrespective of the slackness or tightness of the hawser, which is obviously under a 10 variable pull in a rough sea, in which case the cross-beam 12 will be constantly traveling back and forth and swinging from side to side.

I preferably deliver the coal or other material in sacks, as shown in Fig. 7, each sack 15 having a rope or other flexible line 38 looped about it and adapted to receive a loop 39 connected to the opposite levers of a pair of suspending tongs 40, one lever of the tongs having a hook 41 for engaging over the cable, 20 The loops 38 and 39 are detachably connected together by a pin 42 which is preferably of conical form and attached to the suspending tongs in order that it may not be accidentally lost. The operators standing on 25 the platforms 31 apply the sacks to the suspending tongs engaged over the cables at intervals, and as these cables travel to the receiving mechanism by the operation of the motors 24 and 29, the operators standing on 30 the platforms 32 and 33 withdraw the pins 42 as the suspending tongs strike the stops 32^a and 33^a, thus releasing the sacks; these stops operating to bring the tongs to a standstill and permitting of the cables sliding 35 therethrough until the tongs are released and placed upon the upper length of the cable for the return trip.

By maintaining the cables under an equalized and constant tension, the transfer may 40 be carried out with safety under the most unfavorable circumstances.

Having thus described my invention, I claim as new and desire to secure by Letters Patent:

45 1. In an apparatus for transferring at sea, material from one ship to another, the combination of sheaves carried by one of the ships, a cross-beam slidably and swingingly mounted, carried by the other ship and having sheaves at its opposite ends, continuous cables passing over the sheaves from one ship to the other, on which the material is carried, and a weight connected to the cross-beam for equalizing the strain on the cables 50 and maintaining them under constant tension.

55 2. In an apparatus for transferring at sea, material from one ship to another, the combination of a frame carried by one of said ships, a beam slidably and swingingly supported on said frame, having sheaves at its opposite ends, a frame carried by the other ship, sheaves carried on the last mentioned frame, cables passing over the sheaves from 60 one ship to the other, on which the material

is carried, and means normally forcing the beam in a direction to maintain the cables under tension.

3. In an apparatus for transferring at sea, material from one ship to another, the combination of a slotted frame, a cross-beam freely slideable longitudinally of the ship in the slots of the frame, sheaves carried by the cross-beam at the outside of the frame, sheaves attached to the cross-beam at each 70 side of its center on the inside of the frame, a roller journaled at the forward end of the frame, a frame carried on the other ship and having sheaves, cables passing from one ship to the other over the last mentioned sheaves 75 and the sheaves at the ends of the cross-beam, a frame arranged on said other ship in advance of the last mentioned frame and having sheaves, cables passing from one ship to the other over the last mentioned sheaves 80 and the sheaves attached to the cross-beam at the inside of the first mentioned frame, and a weight having a connection with the cross-beam, passing over said roller.

4. In an apparatus for transferring at sea, material from one ship to another, the combination of a cross-beam carried by one of the ships and slidably and swingingly supported, sheaves carried on the opposite ends of the cross-beam, sheaves carried by the 90 other ship, cables between the ships, passing over said sheaves, means forcing the beam in a direction to keep the cables under tension, hangers detachably engaging with the cables, on which the material to be transferred 95 is carried, platforms arranged adjacent to each of the sheaves for supporting the operators, and a chute for receiving the material, leading from one of the platforms.

5. In an apparatus for transferring at sea, material from one ship to another, the combination of a traveling cable, tong hangers having means at one end of its levers for engaging the cable, a flexible loop attached to the opposite end of the levers, a sack for carrying the material, having a flexible loop thereabout, and a pin for detachably connecting the two loops together. 105

6. In a transporting apparatus, the combination of a plurality of endless cables for 110 transporting and sustaining loads during their transit, and operatively connected means for maintaining all of the cables under approximately constant tensions.

7. In an apparatus for transferring at sea, material from one ship to another, the combination of sheaves carried by one of the ships, a beam slidably and swingingly mounted on the other ship, sheaves carried by the beam, traveling continuous cables 115 passing over the sheaves from one ship to the other, and means attached to the beam for maintaining the cables under approximately equal and constant tensions.

8. In a transporting apparatus, the com- 120

bination of a plurality of endless cables for transporting and sustaining loads during their transit, and means for maintaining all of the cables under tension, operating to automatically relieve one of the cables of undue strain and take up the slack in another of said cables.

In testimony whereof I have signed my name to this specification in the presence of two subscribing witnesses.

ANDREW JOHAN.
